James F. Williamson

UNITED STATES PATENT OFFICE.

FRANKLIN L. BARBER, OF CHICAGO, ILLINOIS, ASSIGNOR TO STANDARD CAR TRUCK COMPANY, A CORPORATION OF NEW JERSEY.

DRAWBAR BUFFER.

Application filed August 24, 1923. Serial No. 659,117.

This invention relates to a drawbar buffer, such as now commonly used on railway cars. In the patent granted to John C. Barber May 25th, 1920, No. 1,341,455, a structure of 5 drawbar buffer was disclosed in which said buffer has its forward end in the shape of a yoke embracing the coupler shank, which shank was supported on a bracket universally movable and in a substantially horizontal plane and hung from said buffer on swinging rods or bolts. The buffer body and said bracket were provided with recesses accommodating the swinging movements of the bolts. The nuts commonly used 10 on the bolts have, in practice, been secured by cotter pins passing through said bolts. It has been found, in practice, however, that the cotter pins sometimes break or are lost out and the swinging movement of said 15 bracket and bolts resulting in rotation of the bolts and nuts so that the nuts are moved on or lost from the bolts and the support for the bracket which holds the coupler shank is thus changed or entirely removed.

It is an object of this invention, therefore, to provide a structure similar to that disclosed in the above patent in which, however, the supporting bolts for the bracket which supports the coupler shank have 20 thereon means for preventing relative rotation of the bolts, or nuts, with buffer body and bracket.

It is also an object of the invention to provide such means carried by the bolts both 25 adjacent their headed portions and adjacent the nuts thereon.

It is more specifically an object of the invention to provide such means comprising semi-spherical members seated, respectively, 30 on the buffer body and said bracket, which members have means thereon engaging the bolt heads and the nuts on the bolts, respectively, and which also engage the buffer body and said bracket, respectively.

These and other objects and advantages of 35 the invention will be fully set forth in the following description made in connec-

tion with the accompanying drawings in which like reference characters refer to the same parts throughout the different views, 50 and in which,

Fig. 1 is a view in end elevation showing the drawbar buffer and the parts of the car to which the same is attached with the invention applied thereto;

Fig. 2 is a vertical section taken on the line 2—2 of Fig. 1, as indicated by the arrows;

Fig. 3 is a horizontal section on the line 3—3 of Fig. 2, as indicated by the arrows;

Fig. 4 is a plan view of one of the parts used; and

Fig. 5 is a vertical section taken on the line 5—5 of Fig. 4, as indicated by the arrows.

Referring to the drawings, the channel and sill of the railway car is designated as 1 on which is carried the buffer member 2. The member 2 is formed with a central yoke-like part comprising the side portions 3 and 70 the top portion 4, which parts are reinforced or made heavier in cross section, the sides 3 comprising comparatively narrow portions against which the coupler shank 5 is adapted to contact in its swinging movement. The buffer 2 comprises, at each side of said yoke, bosses 6 provided at their upper ends with semi-spherical surfaces 8 in which seat semi-spherical members 7, which members are apertured to receive and carry 80 the bolts 9 passing therethrough and through downwardly flaring recesses 10 in the bosses 6. The nuts 11 support other semi-spherical members 7 similar to the members 7 above mentioned, which latter 85 members are seated in semi-spherical recesses formed in the sides of a bracket member 13 extending between said bolts having a recess portion in which seats the coupler shank 5, which shank is thus supported by 90 said bracket. Above the semi-spherical recess therein the bracket 13 is provided with upwardly flaring openings 14 through which the bolts 9 pass. The buffer body 2 adjacent

the tops of the bosses 6 is provided with an outwardly projecting lug having formed therein a recess 15 and the upper members 7 have a laterally projecting pin or lug 16 which seats loosely in said recess. Said members 7 also have an upwardly projecting segmental portion 17 thereon having a flat inner surface which lies closely adjacent one flat side of the heads of the bolts 9. The bracket 13 also has formed at each side thereof a recess 18 and the pin 16 on the lower member 7 is disposed loosely in said recess. The lower members 7, likewise, have the segmental portions 17 with the flat shoulder forming surface thereon, which surface lies close to one flat side of the nuts 11.

In operation, the coupler shank, as stated, is supported on the swinging bracket 13 and said bracket is permitted to have universal swinging movement substantially in a horizontal plane, thus accommodating all movements of the coupler shank 5. The coupler shank moves with the bracket 13 and all wear between the coupler shank and its support is thus eliminated and the wear on the coupler knuckles is, by the movement of the coupler and its shank, thus greatly lessened. The flat surfaces on the portion 17 of the upper members 7 prevents any relative rotation of the bolts and said members and the projection 16 on the members 7 will engage with the sides of the recess 15 in any considerable movement of the members 7 and will prevent any relative rotation between said members and the buffer body. The projection 16 normally does not engage the sides of the recess 15 and in any forward and rearward movement of the bracket 18 and bolts 9, said projection will merely swing through a small arc in a forward and rearward direction. The said projection also normally does not engage the bottom of the recess 15 and in any lateral swinging of the bracket 18 and bolts 9 said projection will merely have a short up-and-down rocking movement. The bolts 9 and the brackets 18, of course, swing about the semi-spherical surfaces on the members 7 and in the buffer body and bracket, respectively. The flat surfaces on the portions 17 on the lower members 7 will engage the flat surfaces of the nuts 11 and prevent any relative rotation between the members and nuts while the projection 16 on the lower member 7 will, if moved to any considerable extent, engage the walls of the recess 18 and prevent any relative rotation of the members 7 and bracket 13. The projection 16 on the lower members 7 normally is out of contact with the walls of recess 18 so that all movements of the bracket and bolts will be accommodated. It should be noted that the bracket 13 normally is spaced below the bottom of the buffer body 6. The bracket can therefore be raised and the nuts 11 adjusted as desired, and the cotter pins (not shown) placed in the openings 12 after which the bracket can be allowed to descend to its normal position bringing the projection 16 into the recesses 18 and the flat surface of segments 17 in proximity to the flat surfaces of the nuts 11. It is thus seen that any rotative movement of the bolts 9 is prevented and there is no danger of the nuts 11 moving on the bolts 9 or moving off of the same. The cotter pins will thus not be broken or sheared off or if the same be lost the nuts will still not be lost off the bolts. A very secure and safe structure of buffer and coupler shank carrying bracket is thus secured. The members 7 can be easily cast and the recesses 15 and 18 can easily be cast in the members 6 and 13, respectively. The invention can thus be applied to the buffer and its parts with practically no additional expense. The parts of the device are easily and quickly assembled and installed on the car.

It will, of course, be understood, that various changes may be made in the form, arrangement, details and proportions of the parts without departing from the scope of applicant's invention, which, generally stated, consists in a device capable of carrying out the objects above stated and such as shown, described and set forth in the appended claims.

What is claimed is:

1. A drawbar buffer having a body yoke-like in cross section and embracing a coupler shank, a bracket underlying said body and supporting the coupler shank, a pair of bolts having a universal connection with said bracket for supporting said bracket from the buffer for universal movement substantially in a horizontal plane, and means on said bolts engaging said buffer body to prevent relative rotation of said bolts and said buffer body.
2. A drawbar buffer having a body yoke-like in cross section and embracing a coupler shank, a bracket underlying said body and supporting the coupler shank, and a pair of bolts having a universal swinging connection with both said body and bracket supporting said bracket from the buffer for universal movement substantially in a horizontal plane, nuts on said bolts supporting said bracket, and means for preventing relative rotation of said nuts and bracket.
3. A drawbar buffer having a body yoke-like in cross section and embracing a coupler shank, a bracket underlying said body and supporting the coupler shank, and a pair of bolts supporting said bracket from the buffer for universal movement substantially in a horizontal plane, means on said bolts engaging said buffer body to prevent

relative rotation of said bolts and body, nuts on said bolts and means on said bolts engaging said bracket to prevent relative rotation of said nuts and bracket.

5 4. A drawbar buffer having a body yoke-like in cross section and embracing a coupler shank, a bracket underlying said body and supporting the coupler shank, a pair of headed and nutted bolts supporting said bracket from the buffer for universal movement substantially in a horizontal plane, said bolts having adjacent the heads members having semi-spherical surfaces seated in correspondingly formed recesses in the top 15 of said body, said members each having a flat surface lying adjacent a flat surface on the head of its bolt to prevent relative rotation of said bolt and member, and each of said members also having a laterally extending projection disposed in a recess formed in said body to prevent relative rotation of said members and body.

5 5. A drawbar buffer having a body yoke-like in cross section and embracing a coupler shank, a bracket underlying said body and supporting the coupler shank, a pair of headed and nutted bolts supporting said bracket from the buffer for universal swinging movement substantially in a horizontal 20 plane, said bolts having thereon adjacent the nuts thereon members with semi-spherical surfaces seated in correspondingly formed recesses in the bottom of said bracket, said members each having a flat surface lying adjacent the flat surface on its nut to prevent relative rotation of said nut and member and each of said members also having a laterally extending projection disposed in a recess formed in said bracket to prevent relative rotation of said members and bracket.

45 6. A device of the class described comprising, a headed bolt adapted to support a member thereon, a supporting means carrying said bolt, a member on said bolt adjacent its head contacting said means and supporting said head, said last mentioned member having a flat surface lying close to a flat surface on said head and having a laterally projecting portion disposed in a recess 50 formed in said supporting means.

55 7. A device of the class described, comprising a supporting bolt, means carried on said bolt, a nut on said bolt, a member on said bolt supported by said nut and contacting said means having a flat surface lying close to a flat surface on said nut and having a lateral projecting portion disposed in a recess in said means to prevent relative rotation of said nut, member and means.

60 8. A device of the class described comprising a headed supporting bolt, a member through which said bolt passes having at its top a flat surface to receive said head and on which said head rests and having a lug 65 adapted to be contacted by said head where-

by relative rotatable movement of said bolt and member is prevented, a support on which said member rests and is universally movable, and means carried by said member engaging said support to prevent relative rotative movement of said member and support.

9. A device of the class described comprising, a supporting bolt, means supported by said bolt, a nut on said bolt, a member on 75 said bolt supported by said nut and contacting said means, said member being formed to engage said nut and prevent relative rotation of said nut and member and said member also having means loosely engaging said 80 first mentioned means to prevent relative rotation of said member and said first mentioned means.

10. A drawbar buffer having a body yoke-like in cross section and embracing a coupler shank, a bracket underlying said body and supporting the coupler shank, a pair of members supporting said bracket having means thereon with ball and socket engagement with said body and also means thereon 90 with ball and socket engagement with said bracket whereby said bracket can swing universally in a substantially horizontal plane, said member and means being held against rotative movement relative to each other. 95

11. The structure set forth in claim 10, said means also being held against rotative movement relative to said body and bracket, respectively.

12. A drawbar buffer body yoke-like in 100 cross section and embracing a coupler shank, a bracket underlying said body and supporting the coupler shank, a pair of headed bolts, a member mounted on each of said bolts resting on said body and forming therewith a 105 universal joint, the heads of said bolts resting respectively on said members, said bolts passing through said bracket, a member mounted on the lower end of each of said bolts on which said bracket rests and forming a universal joint with said bracket, and nuts on said bolts on which said last mentioned members rest, said first mentioned members having means engaging said bolt heads to prevent relative rotative movement 110 of said members and bolts, and said last mentioned members having means engaging said nuts to prevent relative rotative movement of said last mentioned members and nuts. 115

13. A drawbar buffer body yoke-like in 120 cross section and embracing a coupler shank, a bracket underlying said body and supporting the coupler shank, a pair of headed bolts, a member mounted on each of said 125 bolts resting on said body and forming therewith a universal joint, the heads of said bolts resting respectively on said members, said bolts passing through said bracket, a member mounted on the lower end of each 130

of said bolts on which said bracket rests and forming a universal joint with said bracket, and nuts on said bolts on which said last mentioned members respectively rest, said body and said last mentioned members having means thereon engaging said bracket to prevent relative rotative movement of said members and bracket.

5 first mentioned members having means thereon engaging said body to prevent relative rotative movement of said members and In testimony whereof I affixed my signature.

FRANKLIN L. BARBER.
